B. F. SEYMOUR.
EXTENSIBLE MAST.
APPLICATION FILED DEC. 30, 1916.

1,286,807.

Patented Dec. 3, 1918.

THE NORRIS PETERS CO., PISOT'S-LITHO., WASHINGTON, D. C.

UNITED STATES PATENT OFFICE.

BENJAMIN F. SEYMORE, OF DENVER, COLORADO.

EXTENSIBLE MAST.

1,286,807.

Specification of Letters Patent. Patented Dec. 3, 1918.

Application filed December 30, 1916. Serial No. 139,833.

To all whom it may concern:

Be it known that I, BENJAMIN F. SEYMORE, a citizen of the United States, residing at Denver, in the county of Denver and State of Colorado, have invented certain new and useful Improvements in Extensible Masts, of which the following is a specification.

My invention relates to extensible masts which will be found useful in warfare and for commercial and other purposes, and the invention consists of the parts and the constructions, arrangements and combinations of parts which I will hereinafter describe and claim.

A leading object of the present invention is to provide an improved mechanism, of simple and highly practical construction by means of which an object, whatever its nature and whether designed for warfare or commercial uses, may be elevated to a considerable height above a surface upon which the mast is erected. The character of the object mounted on the mast is immaterial, but in practice I prefer that the mast shall contain a platform which will be designed as a support for the object, or contrivance, and which may also serve as an observation platform from which the surrounding country may be inspected, this phase of the invention and in fact many of the leading parts of the present structure, being not essentially unlike the corresponding parts and the operations thereof, which are fully described in my copending applications, Ser. No. 65,725, filed December 8, 1915, and Ser. No. 75,772, filed February 2, 1916. In other words, it is understood that in the present case the mast may be supplied with such accessories, contrivances, and operating means as are indicated in the aforesaid applications, and for the sake of simplicity these contrivances and the operations of the same are not herein set forth in detail.

In the accompanying drawings forming part of this specification and in which similar reference characters indicate like parts in the several views:—

Figure 1 is a side elevation of a sectional mast showing the sections thereof in their extended position.

Fig. 2 is an enlarged side elevation, par-

tially in section, of the base section and portions of intermediate sections in their extended position.

Fig. 3 is a side elevation of the mast in its folded condition.

Fig. 4 is a cross sectional view on the line 4—4 of Fig. 1.

As in my aforesaid prior applications, the present mast is of an extensible character and is formed of a base-section and a plurality of sections adapted to telescope, each of said latter sections comprising a plurality of rotatably connected tubular members, with the exception of the upper section, the members of which are relatively stationary and may, if desired, be made of solid material, the arrangement of the sections being such that a rotary movement imparted to the members of one of the sections will result in successive upward or downward movements of other sections, according to the direction of rotation of the first-named sections.

The lower or base section of the mast is composed of a plurality of parallel tubular parts *a*, *a'*, the former of which is rigidly secured upon a floor or platform *b*, upon which the mast is erected, and which platform or floor may represent the corresponding part of a vehicle of any desired type upon which the structure is designed to be mounted and by which it may be transported from place to place. This platform, of course, may be stationary and in fact it may represent any suitable support capable of properly sustaining the mast in either its extended position as in Fig. 1, or when the sections are collapsed or telescoped as in Fig. 2.

At the top of the tubular members, *a*, and within an appropriate casing or housing, 12, are contained appropriate nuts, 14. In the present arrangement I have shown the structure as comprising four lower tubular members suitably spaced apart and a centrally disposed member, *a'*, which latter serves as a driver for the other members of the base section and to this end the central member carries a beveled or other gear, 15, which is in mesh with and is driven by a gear 17, which has a crank-handle, 18, or other appropriate driving element.

The nuts, 14, are loosely mounted on the

upper ends of the uprights, while a nut, 14', is fixedly secured on the upper end of the central upright, a', and which latter is positively driven as before stated. The nuts are 5 of any well known type and may be in the form of gear-wheels which intermesh as indicated in Fig. 4, and they have central openings which are internally threaded to thus adapt them for the operative connection 10 with the threaded or spirally grooved shafts, 19, 19', of the lowermost movable section of the mast, the arrangement being such that when the operating means shown at the base of the mast is operated, rotation 15 is imparted to the central upright, a', and through the geared nut, 14', at the top thereof rotation is given the loose nuts, 14, with the result that rotative movement is thereby imparted to the sections, 19, before mentioned. 20

Each of the threaded shafts, 19, carries at its upper end a fixed gear-nut, 20, and the intermediate shaft also carries at its upper end a fixed gear, 21', which meshes 25 with the gears, 20, these gears being internally threaded to adapt them for appropriate operation with the spirals or threads formed on the shafts 22 of the next succeeding section of the mast, this section having 30 its shafts adapted to telescopically fit within the corresponding shafts, 19, of the lower section, and the intermediate shaft, 22', of this section being designed for telescopic movement within the corresponding intermediate shaft, 19', of the next lower section, 35

The mast may include as many sections constructed and arranged as before described and adapted to telescope one within the other as may be found necessary for the 40 particular use to which my invention is to be put, and the height to which the object or contrivance which the mast is to carry is to be elevated. In the present drawings I have shown two additional sections, one 45 illustrated at 25, as operated by gear-nuts, 24, on the shafts, 22-22', the members of said section, 25, carrying gear nuts, 26, at their upper ends; and a top section, 27, the upper ends of whose shafts are connected 50 by a platform or support, 28, the construction being such that the shafts of the upper section are held against rotation, but the shafts constituting this uppermost section are given the rectilinear movement due to 55 the rotation of the gear nuts, 26, of the next lower section, as will be understood in this art.

In order that each succeeding section may be substantially locked against further rotation at the limit of its upward extension, 60 I may form on the lower ends of the sections collars, 29, which are designed to abut against the hubs of the gear-nuts of the next lower section, as indicated in Fig. 3,

so that when a section is elevated to its 65 extreme limit, the further movement of the shafts thereof is checked and the shafts thus become locked to the companion nuts and the nuts and shafts may then turn together and by so doing rotation is imparted to the 70 nuts carried at the top of the next higher section with the result that the threaded shafts engaging the nuts of the last mentioned section will be actuated in the direction of their length. 75

It will be understood from the foregoing that the mast may be composed of any desired number of sections of suitable length within the limits of the diameters of their members, which necessarily decrease progressively from the base section to the upper section of the structure; that the members constituting the lower or base section and the members constituting the uppermost section are non-rotatable and that said upper section supports the contrivance with which the mast is to be supplied. This contrivance, in the present instance, is shown as a searchlight 30, of any appropriate character and which is so suspended by links or a lever mechanism, 31, that it may be elevated to a position on top of the platform, when it is in active use, or it may be removed from this platform and deposited upon an appropriate support, 33, on the platform of the vehicle or supporting structure, when the mast is collapsed and the sections telescope one within the other, as indicated in Fig. 2. The means for operating the searchlight are unimportant since I 100 will adopt any construction for this purpose which will best serve the object of the invention. It is also understood that any other contrivance may be substituted for the searchlight and to this end I may employ any kind of contrivance and operating means disclosed in detail in my aforesaid prior applications. 105

In operation and assuming that the sections are in their collapsed position, as in Fig. 2, when the crank handle of the operating means is turned, the intermediate tubular member, a', and the intermediate shafts, 19' and 22', of the several sections, except 110 the uppermost section, are rotated and as the geared nuts on the upper ends of these various screw-shafts are in mesh with the similar gear-nuts on the upper ends of the companion screw shafts, it will be apparent 115 that the several sections will be successively advanced out of each other, following the upper contrivance supporting section first advanced out of its section and until the parts have assumed substantially the position shown in Fig. 1. A reverse operation 120 will result in the several shafts constituting the various sections being telescoped one within the other, as indicated in Fig. 2, after 125

which the searchlight, or other contrivance, may be swung from its position on top of the uppermost section to the support of Fig. 2.

5. In the present instance the specific improvement is largely in the employment of the gear-nuts at the top of the shafts constituting the various sections and which nuts constitute a directly geared connection between the several shafts of each section and to an extent control the movement of each section.

Having thus described my invention what I claim as new and desire to secure by Letters Patent is:

1. An elevator comprising a plurality of parallel, substantially closely spaced telescoping sections; a driving section parallel with and intermediate of the first named sections; intermeshing gears on the upper ends of said section, for raising and lowering said sections; and auxiliary gear means on companion sections co-actively engaged and adapted to convert their rotary movement into longitudinal movement of the sections.

2. An elevator comprising a plurality of parallel, substantially closely spaced telescoping sections; a driving section parallel with and intermediate of the first named sections; intermeshing gears on the upper ends of said section, for raising and lowering said sections; and auxiliary gear means on companion sections co-actively engaged and adapted to convert their rotary movement into longitudinal movement of the sections, a support on the uppermost section, a contrivance adapted to be mounted on said support, and pivotal means shiftably mounting the contrivance relatively to the support.

3. An extensible mast comprising a plurality of parallel, substantially closely spaced telescoping sections; a driving section parallel with and intermediate of the first named sections; intermeshing gears on the upper ends of the sections, for raising and lowering the latter; and rotatable gears on the sections engageable with each other and forming an auxiliary sectionally mounted means for converting the rotation of the gears into rectilinear movement of the sections.

4. An extensible mast comprising a plurality of parallel, substantially closely spaced telescoping sections; a driving section parallel with and intermediate of the first named section; intermeshing gears on the upper ends of the sections, for raising and lowering the latter; and rotatable gears on the sections engageable with each other and forming an auxiliary sectionally-mounted means for converting the rotation of the gears into rectilinear movement of the sec-

tions, and a contrivance and means connected therewith for shifting the contrivance relatively to certain of the sections.

5. An extensible mast comprising a plurality of rotating and non-rotating sections, certain of said sections being centrally disposed between the other sections; means for rotating certain of said sections; and intermeshing gearing on the sections and connecting the members of each section in series, and forming an auxiliary sectionally-mounted means for the extension and contraction of said sections.

6. An elevator comprising a plurality of substantially closely spaced telescoping sections, certain of said sections being centrally disposed between the other sections and each of said sections having intermeshing gears; means for applying power to said elevator; and means on the sections engaged with each other and successively engaging the sections and adapted to raise and lower said sections.

7. An elevator formed of sections, said sections comprising a plurality of substantially closely spaced parallel members and a centrally located intermediate driving member; and means including co-acting gearing on said members for converting rotation of the driving member into rectilinear movement of said members.

8. An extensible mast comprising a base section, other sections telescopically arranged relatively to each other and to said base section, said other sections having spiral threads, a rotatable driving section of telescopic members arranged intermediate of said other sections, and co-acting gear elements on said other sections and said driving section, said gear elements of one section engaging the spiral thread of a co-acting section for converting the rotation of the driving section in relative rectilinear movement of said sections.

9. In an extensible mast, the combination with a non-rotatable base and a top section, of other sections intermediate of the top and base sections, said intermediate sections being formed of spirally grooved telescoping shafts, a driving section formed of rotatable telescoping shafts arranged parallel to and intermediate of the other shafts, and co-acting gear-means on corresponding portions of the said shafts and operatively engaging the spiral grooves of the first-named shafts and thereby rectilinearly moving the latter.

10. In an extensible mast, the combination with a base section and a top section, each composed of non-rotatable members; of other sections intermediate of and aligned with the base and top sections, and composed of spirally grooved telescopically-fitted shafts, a driving section centrally disposed between the other sections and formed

of telescopically fitted rotatable shafts arranged parallel to the other shafts and sectionally substantially corresponding to the latter, said first-named shafts having their 5 spiral grooves relatively reversed, and co-acting gears on the corresponding portions

of the first and second named shafts, said spirally grooved shafts having means engageable with said gears to thereby lock the shafts thereto. 10

In testimony whereof I affix my signature.

BENJAMIN F. SEYMOUR.
